(57) **CLAIM**

The ornamental design for a sun visor cover, as shown and described.

DESCRIPTION

FIG. 1 is a top, front, right perspective view of a sun visor cover, showing my new design;

FIG. 2 is a top, rear, left view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The broken lines illustrate portions of the sun visor cover which form no part of the claimed design.
